UNITED STATES PATENT OFFICE.

FRANK T. KENNEDY, OF OMAHA, NEBRASKA, ASSIGNOR TO THE CUDAHY PACKING COMPANY, OF SOUTH OMAHA, NEBRASKA, AND CHICAGO, ILLINOIS.

DESIGN FOR A CAN OR BOX.

SPECIFICATION forming part of Design No. 33,891, dated January 8, 1901.

Application filed December 11, 1900. Serial No. 39,565. Term of patent 14 years.

To all whom it may concern:

Be it known that I, FRANK T. KENNEDY, a citizen of the United States, residing at Omaha, in the county of Douglas and State of Nebraska, have invented and produced a new and original Design for Cans or Boxes, of which the following is a specification.

My invention relates to a new and original design for cans or boxes, and is illustrated in the accompanying drawings, in which—

Figure 1 is a perspective view, and Fig. 2 is a top plan view.

The leading features of my invention reside in a can or box having the general shape of an approximation of a truncated shield, one end of the can or box being narrow and plain or flat and the sides extending in gradually-widening curved lines to the top, which is formed at its opposite ends with convex elevations and a middle elevation of greater height separated from the end elevation by concavities.

In the said drawings the numeral 1 indicates the can or box, which has approximately

the general formation of a truncated shield. 25 One end 2 of the can or box—the truncated end—is narrow as compared with the remaining portions of the box and is plain or flat. The sides of the box extend from the truncated end in gradually-widening convex lines 30 3 to the top, which is formed at its opposite ends with convex elevations 4 and a middle elevation 5 of greater height than the elevations 4 and which is separated from the last-named elevations by concavities 6. 35

My design presents a can or box of novel, ornamental, and pleasing appearance.

Having thus described my invention, what I claim is—

The design for a can or box, substantially 40 as herein shown and described.

In testimony whereof I have hereunto set my hand in presence of two subscribing witnesses.

FRANK T. KENNEDY.
